UNITED STATES PATENT OFFICE.

WILLIAM B. KOCHENDERFER, OF CAMDEN, NEW JERSEY.

HYDRAULIC PRESS.

Application filed October 28, 1921. Serial No. 511,213.

My invention relates to vertically-disposed, hydraulically operated two-pressure compressing mechanism, and one object of my invention is to provide a structure of this type particularly arranged for de-hydrating masses of boiled garbage, packing-house tankage, or other matter of similar nature, pulpy or otherwise, to be de-hydrated; the liquid content thereof draining or flowing off during the compressing action.

A further object of my invention is to provide means for delivering measured quantities of material to the compressing chamber.

15 A further object of my invention is to provide special valve mechanism whereby I can assure complete separation of the material in the tanks from that in the delivery spouts leading to the press; such valve mechanism also including a mechanically operated cut-off of a type capable of shearing any character of foreign material; metallic or otherwise, associated with the garbage or other material to be de-hydrated.

25 A further object of my invention is to provide special means for draining off the liquid portion of the boiled garbage, tankage, or other material operated upon, in an efficient and cleanly manner, and to provide 30 means for straining the same, in order that the final effluent may pass to any water course without danger of polluting the same or filling it with solid material.

35 And a still further object of my invention is to provide simple and efficient means for discharging compressed bodies of the garbage; tankage, or the like, from the press.

These and other features of my invention are more fully described hereinafter; reference being had to the accompanying drawings, in which:

40 Fig. 1, is an elevation, partly in section, of hydraulic compressing mechanism within the scope of my invention.

45 Fig. 2, is an enlarged elevation of a portion of the structure shown in Fig. 1, partly in section on the line II—II.

50 Figs. 3, 4 and 5, are sectional plan views on the lines III—III, IV—IV, and V—V, Fig. 2.

55 Fig. 6, is an elevation, partly in section on the line VI—VI, Fig. 2, and

Fig. 7, is an elevation at right angles to Fig. 2, partly in section, illustrating a modification within the scope of my invention.

In the disposition of boiled garbage, tank-

age, and the like, it is essentially necessary to dispose of the liquid content thereof. It is desirable from many standpoints that this be done in an efficient and cleanly manner, and in addition to many important details of construction, the structure forming the subject of my invention has been especially designed for this purpose.

In the drawings, 1 represents the cylinder of an hydraulic press, containing a ram or plunger 2, to the upper end of which a compressing head 3, may be attached; the latter being arranged for movement within a compressing chamber 4, formed in a cylinder 4^a. A perforated drainage plate 5, may be disposed upon the engaging face of said head 3, and suitably secured thereto; said head 3 or the plate 5, being provided with ribs 6 to provide drainage channels 7, whereby the liquid content of the material being compressed may be carried off. At the opposite end of the structure, in the present instance the upper end, a second cylinder 10, is provided, within which may be disposed a second ram or plunger 11, having a head 12, adapted to fit into the upper end of the cylinder 4^a and close the compressing chamber 4.

Fluid under pressure to lower the ram or plunger 11, and raise the ram or plunger 2, may enter the respective cylinders 10 and 1, from any suitable source and under special valve control, as hereinafter set forth. The pressure which lowers the ram or plunger 11, holds the same in fixed position with respect to the cylinder 10, during the compressing operation. To raise the ram or plunger 11, I may provide auxiliary cylinders 13, disposed adjacent the cylinder 10, and having pistons therein which are positively moved in the upward direction only, by fluid entering via pipes 14; such fluid exhausting through the same pipes by way of special valves which may be alternately 100 inlet and exhaust valves, as required. These pistons (not shown) are carried by piston rods 15, which may be connected at 16, to arms 17, projecting laterally from the plunger 11.

The chamber 4 of the compressing mechanism is arranged to receive boiled garbage, tankage, or the like, from a suitable receptacle (or receptacles) disposed above the same so that the material to be compressed may be delivered by gravity, and by preference this chamber is arranged to receive

such material from a pair of tanks, indicated at A and B.

For the purpose of delivering the boiled garbage, tankage, or other material to be compressed, to the chamber 4, in a cleanly manner and without danger of the liquid content leaking over the apparatus, I provide a receiving chamber 20, above the compressing chamber 4, and such receiving chamber 10 may be formed by a movable skirt or casing 21, which is in engagement with the cylinder 4^a, during the filling and compressing operations; being raised when it is desired to discharge the compressed "cheese" 15 of garbage, tankage, or the like, in the manner hereinafter described.

Communicating with the receiving chamber 20, is a delivery spout 22, leading from the elevated receptacle. By preference I 20 provide a pair of spouts through which the material to be compressed may be delivered from the tanks A and B; which spouts are properly valved to facilitate proper and regulable discharge of the material contained 25 in said tanks. At the points of delivery from the tanks, special hydraulically-operated shearing valves 23, are preferably provided for the purpose of cutting off cleanly the material discharged from the tanks; said 30 shear valves being of a character capable of severing any hard body of any nature that may be found with the boiled garbage or tankage. These valves have a cutting edge 23^a, and they may be operated by a piston 35 23^b in a cylinder 23^c.

At the lower end of each delivery spout I may provide an hydraulically operated gate valve 24, which are closed while either spout is filling from its tank. As soon as 40 a spout fills, its shearing valve may be closed, and after this has been done, its gate valve may be opened, and the contents of such spout will discharge into the compressing chamber 4, through the casing 21 of the 45 receiving chamber 20, when the compressing chamber is ready to receive the same; that is to say, when the ram or plunger 2 has been lowered to provide the space to receive the garbage or tankage.

50 Before the gate valve 24 has been opened to admit the garbage to the compressing chamber, the ram or plunger 11 has been raised, by the admission of pressure to the auxiliary cylinders 13; pressure to move the 55 pistons in said cylinders being introduced through the pipes 14, and such pressure is constant until low pressure is admitted to the cylinder 10 and causes the ram or plunger 11 to lower whereby its head 12 may 60 close the upper end of the cylinder 4^a containing the compressing chamber 4.

The movable skirt or casing 21, forming the chamber 20, is provided with apertures or openings 25, on opposite sides, which 65 register with the valved discharge outlets of

the respective delivery spouts 22. After material from either spout has discharged into the compressing chamber 4, the gate valve of such spout is closed, and then the ram or plunger 11, with its head 12, is caused 70 to descend by admission of low pressure to the cylinder 10, via a pipe 26; the latter pressure overcoming the constant pressure in the pull-back cylinders 13, the pistons of which serve to maintain the ram or plunger 75 11 in the elevated position.

Both of the cylinders 1 and 10 are open to pressure from the same source but under separate valve control, and as soon as the head 12 of the upper ram or plunger 11 is 80 in place, low pressure is introduced into the lower cylinder 1, via a pipe 27, from a common source, and by preference the valve controlling this admission of pressure is of such a character that when the compressing 85 plunger 2 has effected the maximum compression under low pressure it will automatically change its position, and in such second position it will serve to admit high pressure to both cylinders 1 and 10; holding 90 the upper head 12 in place by reason of the fact that its ram or plunger 11 is of greater area than the ram or plunger 2 carrying the compressing head 3, thereby effecting 95 compression to the maximum degree by the operation of such compressing head until the maximum amount of free liquid contained therein and which can be removed by the tonnage of the press from the boiled garbage or tankage, has been extracted.

100 In the form of structure illustrated in Figs. 1, 2, et seq., the head 12, which fits within the upper end of the compressing chamber 4, is provided with an annular groove 30, which registers with an annular groove 31 formed in the wall of said chamber 4, and by slightly reducing the diameter of the head 12 below said groove 30, an annular space 32 is provided for the passage of the liquid squeezed from the garbage at 110 the top of the mass, as indicated in Fig. 1, and this liquid may pass through outlets 33 formed in the wall of the cylinder 1, to pipes 34. The liquid passing from the mass of garbage or other material at the bottom 115 of the same, may drain through the perforated plate 5, carried by the head 3, and through openings 35 formed in said head; such liquid discharging through outlets 36, formed in the end wall 37, of the cylinder 120 4^a, and passing to pipes 38. The pipes 34 and 38 connect with a main or manifold 39, which in turn may be connected to a double, continuous flow strainer 40, forming 125 part of a suitable drainage system.

In the form of structure shown in Fig. 7, the upper compressing head 12 of the ram or plunger 11, may be provided with a drainage plate 5^a, suitably secured thereto; said plate 5^a, or the head 12 being provided 130

with ribs 6^a, to form drainage channels communicating with the annular groove 31 formed in the wall of the cylinder 4^a, from which the liquid content of the material 5 being compressed may drain through the outlets 33, and pipes 34, to the strainer 40.

The upper ram or plunger 11 is raised by pistons disposed in the auxiliary cylinders 13, which may be supported by the cylinder 10; 10 such ram or plunger 11 being lowered by the low pressure admitted to the cylinder 10 which overcomes the constant pressure in said pull-back cylinders 13. The skirt or casing 21 may be raised and lowered 15 by double-acting pistons disposed in cylinders 41, which may also be carried by the cylinder 10, and which may be disposed at right angles to the cylinders 13. The pistons in said cylinders 41 are connected to piston rods 42, which are in turn connected to the skirt or casing as indicated at 43. Pressure to operate the pistons in the cylinders 41 may enter the same via pipes 44 and 45, and the operation of these pistons is controlled 20 by a valve independent of the valve controlling the pressure to act upon the rams or plungers 2 and 11.

The upper and lower cylinders 10 and 1, and the cylinder 4^a containing the compressing chamber may be connected together by rods or bolts 46; the free ends of which may pass through apertures in flanges 47 and 48, carried by the respective cylinders. These bolts may also pass through apertured bosses 49 carried by the skirt or casing 21. The heads of the cylinders 10 and 1 are suitably packed as indicated at 51 and 52, with the necessary glands 53 and 54 to insure proper joints, and the end wall 37 of the cylinder 4^a may also be packed at 55, with a gland 56, to maintain a tight joint with the lower ram or plunger 2.

After the contents of the compressing chamber have been compressed to the desired extent, the pressure holding the upper compressing head is relieved, and the contents of the chamber may be raised until the lower compressing head is on a level with the upper end of the compressing chamber.

At the same time the upper ram or plunger is lifted by the pistons in the pull-back cylinders 13; the skirt or casing 21 being lifted at the same time by the pistons in the cylinders 41, and the pressed body of garbage, tankage, or the like, usually termed a "cheese" is ready for removal; being supported by the lower ram or plunger at the level of the open end of the cylinder 4^a containing the compressing chamber 4. This

removal may be effected by means of a plunger 58, connected to a suitable piston mounted in a cylinder 59, shown in Fig. 2, which may be provided with the usual piping and connections for the introduction and exhaust of pressure to effect the move-

ment of such piston, (not shown). This cylinder 59 may be supported by a bracket 60, carried by the rods or bolts 46, and the discharged "cheese" may pass to a chute 61, for delivery to a suitable conveyer. 70

It will be noted that the skirt or casing 21 is in place in engagement with the upper end of the cylinder 4^a containing the compressing chamber 4, with the upper compressing head in the upper part of said skirt 75 or casing, when the contents of the delivery spouts are passed to the compressing chamber. By having a pair of delivery spouts it is possible to be filling one from one or a set of cooking tanks while the other is discharging, and vice versa. 80

I claim:

1. In a hydraulic press, the combination of a vertically disposed cylinder, a pair of unobstructed heads vertically movable with respect to said cylinder; the upper head fitting within and serving normally as a closure for one end of the cylinder and the lower head sliding within the cylinder and serving as a compressing element, a plurality of means 85 for delivering fixed charges of material to the compressing chamber, a movable casing closing the upper end of the cylinder and through which such material is charged into the cylinder; said upper head being adapted to operate within said casing out of contact therewith, pressure means actuated from a common source for moving said heads toward each other, auxiliary means for lifting the upper head while the lower head is at rest, and independent means for imparting vertical movement to said casing. 90

2. In an hydraulic press, the combination of a cylinder, a pair of heads movable with respect to said cylinder; one of said heads serving normally as a closure for one end of the cylinder and the other head serving as a compressing element, a movable casing covering the upper end of said cylinder, a delivery spout through which a fixed charge 100 of material may be passed to said casing and thence to the cylinder; said casing surrounding the upper head and being apertured for registry with the delivery spout, and means for raising and lowering said casing to permit the inlet and discharge of material to and from the compressing cylinder. 105

3. In an hydraulic press, the combination of a cylinder, a pair of heads movable with respect to said cylinder; one of said heads being movable within the cylinder and serving normally as a closure for one end of the same and the other head serving as a compressing element; a pair of delivery spouts disposed on opposite sides of the compressing cylinder and through which fixed charges of material may be alternately delivered to the chamber of said cylinder, hydraulically operated valve carried by the 110 115 120 125 130

upper ends of said spouts for controlling delivery through the same, means for moving said heads toward and from each other, and a vertically movable casing having apertures 5 through which the material is delivered from said spouts.

4. The combination, in an hydraulic compressing apparatus for garbage and similar material from which moisture is to be 10 pressed, of a vertically disposed cylinder, a movable head fitting within and serving as a closure for the upper end of said cylinder, a compressing head vertically movable within said cylinder, means for delivering to said 15 cylinder material to be compressed in measured quantities, a movable casing through which such material is charged into the cylinder and in which the upper head is adapted to operate out of contact therewith; 20 the latter being in the raised position during the feeding operation, drainage means carried by each of said heads, means for carrying drained liquid away from the cylinder, and means for discharging the 25 pressed body of material when the latter is raised to the top of the cylinder.

5. In hydraulic compressing mechanism for garbage and the like, the combination of a cylinder forming a compressing chamber, a head axially movable with respect to said chamber and normally closing one end of the same, a movable head within said chamber, independent rams or plungers for independently operating said heads; the 30 head normally closing one end of said chamber occupying a fixed position during compressive movement of the other, provision for carrying off liquid drained through said heads, a spout for delivering 35 material to the compressing chamber, a shearing valve carried by the upper end of said spout, a movable casing carried by the upper end of the compressing chamber and having an opening for registry with the 40 delivery spout, and a plunger at the upper end of the compressing chamber for removing the body of material compressed within 45 said chamber when said body has been lifted to the upper end of the latter.

6. In an hydraulic press, the combination of a vertically disposed cylinder, a pair of unobstructed heads movable with respect to said cylinder; one of said heads fitting within and serving normally as a closure for one end of the cylinder and the other head being movable within the cylinder and serving as a compressing element, means 50 for delivering charges of material to be compressed to the cylinder, a movable casing through which such material is charged into the cylinder and in which the upper head normally closing one end of the cylinder is adapted to operate out of contact therewith, pressure means actuated from a common source for moving said heads, pres-

sure means for moving said casing independently of the upper head, and drainage means carried by the respective heads.

7. In an hydraulic press, the combination of a vertically disposed cylinder, a pair of heads movable with respect to said cylinder; the upper head fitting within and serving normally as a closure for one end of the cylinder and the lower head being movable within the cylinder and serving as a compressing element, a plurality of means for delivering fixed charges of material to the compressing chamber, a movable casing closing the upper end of the cylinder and through which such material is charged into 70 said cylinder; said upper head being adapted to operate within said movable casing out of contact therewith, pressure means actuated from a common source for moving said heads, auxiliary means for raising the 75 upper head independent of movement of the lower head, means for raising and lowering the casing independently of the upper head, and drainage means carried by the 80 respective heads.

8. In an hydraulic press, the combination of a cylinder a pair of heads each vertically movable with respect to said cylinder, one of said heads having a portion fitting within and serving normally as a closure for the 95 upper end of the cylinder and the other head being movable within the cylinder below the upper head and serving as a compressing element, a fixed delivery spout through which measured charges of material may be delivered to the cylinder, a shearing valve carried by said delivery spout, a gate valve also carried by said delivery spout, pressure actuated means for independently operating said valves, and 100 means for actuating both of said compressing heads in a vertical direction.

9. In an hydraulic press, the combination of a cylinder, a pair of heads movable with respect to said cylinder; one of said heads serving normally as a closure for one end of the cylinder and the other head being movable within the cylinder and serving as a compressing element, a movable casing covering the upper end of said cylinder, a delivery spout through which a fixed 110 charge of material may be passed to said casing and thence to the cylinder; said casing surrounding the upper head and being apertured for registry with the delivery 115 spout, cut-off means carried by said delivery spout, and means for raising and lowering said casing to permit the inlet and discharge of material to and from the compressing cylinder.

10. In hydraulic compressing mechanism for garbage and the like, the combination of a cylinder forming a compressing chamber, a head movable axially and normally closing one end of said chamber, a movable 120

head within said chamber, independent rams or plungers for operating said heads, provision for moving the same axially with respect to the upper end of the compressing cylinder; one head occupying a fixed position during the compressive movement of the other, provision for carrying off liquid drained through said heads, a spout for delivering material to the compressing chamber, a shearing valve carried by the upper end of said spout, a gate valve carried by the lower end of said spout, a movable cas- ing carried at the upper end of the compressing chamber and having an opening for registry with the delivery spout, means 15 for raising and lowering said movable casing, and a plunger at the upper end of the compressing chamber for removing the compressed body of material within the compressing chamber when the latter has 20 been lifted to the upper end of the same.

In witness whereof I have signed this specification.

WILLIAM B. KOCHENDERFER.
